CLAIM

The ornamental design for a display panel portion with graphical user interface, substantially as shown and described.

DESCRIPTION

FIG. 1 shows a front view of a first embodiment of a display panel portion with graphical user interface in accordance with the present invention; and,

FIG. 2 shows a front view of a second embodiment thereof. The outermost broken line rectangle illustrates a display panel portion and forms no part of the claimed design. The remaining broken lines illustrate portions of the graphical user interface that form no part of the claimed design.

1 Claim, 2 Drawing Sheets
